Letters Patent No. 72,794, dated December 31, 1867.

IMPROVEMENT IN PREVENTING INCRUSTATION OF STEAM-BOILERS.

The Schedule referred to in these Letters Patent and making part of the same.

TO ALL WHOM IT MAY CONCERN:

Be it known that I, SAMUEL G. CABELL, of the city of Quincy, in the county of Adams, in the State of Illinois, have invented an Improved Apparatus for Removing Incurstations or Scales from the Surface of Steam-Boilers, and for other purposes; and I do hereby declare the following to be a full and exact description thereof, reference being had to the annexed drawing, and the letters explanatory thereon.

In the drawing, A represents the section of an ordinary steam-boiler; B, the steam-dome; C, the steam-pipe; D, the throttle-valve; E, the steam-cylinder; F, the piston; and G, the piston-rod. In the boiler the upper shaded line $z z$ represents the water-level, and the portion above it the steam-chamber, and H the mud-vessel or receiver and pipe.

I have used this form of boiler and engine because the extreme simplicity of its parts enables me to explain the nature of my invention with the greater facility. It is equally applicable to all forms of the steam-engine by adapting it to these forms. Of some of these I shall speak hereafter.

Near the interior surface of the boiler I pass a wire, of silver, copper, iron, steel, or other proper metal, fastening one end to an insulated pin, passing it thence along the crown of the boiler, when the steam is dry, and thence up through the steam-dome to the orifice of the steam-pipe, or near it, where it is joined by another wire from the front of the boiler, which is also insulated from the shell of the boiler by an insulated pin. These two wires being united, as stated, at or near the orifice of the steam-pipe at its junction with the steam-dome, pass singly or doubly along the interior of the pipe to the throttle-valve, where they connect with the throttle-valve stem.

The object of these wires is to conduct the thermo-electricity, produced in the boiler when in operation, to a safe part of the machinery, where it may be disposed of without danger. In stationary boilers, this wire of itself might perhaps be sufficient to accomplish the purpose desired, but on ships, boats, locomotives, &c., their motion would be constantly liable to bring it in contact with the shell of the boiler, which it should not be allowed to do. To prevent this, therefore, I pass the wire through portions of glass tubes or beads, or otherwise enclose it in any non-conducting substance, as seen at $b b$, and at intervals secure metallic points thereto, as seen at $c c$. When the wire has to take a new direction, as in passing from the top of the boiler to the steam-dome, as at e , it is to be supported, to prevent its coming in contact with the metal of the boiler, by an insulated pin, or any other device capable of accomplishing the object. That portion of the wire f , which passes from the pin e to where it comes in conjunction with the other wire f' in the dome, may or may not need covering. To render assurance doubly sure, I insert a cluster of metallic points in or near the mouth of the steam-pipe C, where it connects with the steam-dome. From this point the wire is insulated throughout the steam-pipe to the throttle-valve, substantially as described in speaking of the boiler, and armed with a suitable number of conducting-pipes. Silver having the highest power of conductivity amongst metals, I prefer its use, but copper or even iron or steel may be used for the wire.

It is evident that, by an arrangement of this character, all the electricity or thermo-electricity formed in the steam-cavity or its connecting steam-pipes, must be conducted away quietly, and, if necessary, discharged harmlessly through the throttle-valve stem and its connections to the earth or water.

It has been decided by experimentalists that the introduction of electrical conductors into the steam-cavities of boilers, prevents the precipitations from the boiling water from accumulating in crusts or scales upon the surfaces exposed to the water, these precipitations falling down in an unaggregated or loose state to the bottom. But these matters in that place seriously interfere with the efficiency of the boiler, by interrupting the action of the fire upon the water, and may, by their accumulation of thermo-electricity, be otherwise objectionable. To obviate these difficulties I have devised two plans, which I will proceed to describe.

In the drawing, hereto annexed, I represent the one-half of a screw-formed brush, made of metallic wire on a metallic handle, i , the other half, not represented, having its convolutions in an opposite direction to those shown in the drawing. One or both of the extremities of the handle i pass through a stuffing-box insulated in the end of the boiler, and a revolving motion given to it by means of a crank-handle, i' . The effect of this arrangement is, that, when this screw is set in motion in the proper direction, the precipitated material in the

bottom of the boiler is propelled from both ends of the boiler towards the centre, and deposited in the mud-vessel H, from whence it is blown off by opening the mud-valve attached thereto.

The other plan is to use a broom, K, attached to a handle, k, which also passes through an insulating stuffing-box in the end of the boiler to a handle, k', on the outside of the boiler. This broom is made of metallic wire, and as there are two of them, one on each side of the opening for the mud-vessel H, they may be both worked by one handle, or each by a separate handle, one of which passes through one end and the other through the other end of the boiler. These brooms produce, by their movement back and forth, substantially the same mechanical effect as the screw, that is, remove the accumulated matter in the bottom of the boiler to the mud-vessel H, besides which they draw off, through the attractive influence of their metallic points, all the electricity in this part and in the accumulated precipitations, and discharge it through the conductors L or M into the wires in the interior of the boiler before described. The wire or conductor L makes its connections with the wire f' through an insulating-orifice, l, and M through a similar orifice at a. The other ends of these two wires, L and M, are so connected with i' and k', that the connection between them may be broken at pleasure. The handle k of the broom K passes, like that of I, through an insulating stuffing-box in the end of the boiler.

For greater security, the handle of the throttle-valve, as well as that of the broom k' and that of the screw-crank i', should be made of or protected by some non-conducting substance, such as glass, porcelain, hard rubber, or the like.

Instead of conducting the electric wire, as shown, through the steam-pipe C, it may be passed, by an insulated opening, through the side of the dome directly to the throttle-valve, or to some other proper terminus for discharge to the earth or water.

What I claim, and desire to secure by Letters Patent of the United States, in the above-described invention, is—

1. I claim the application to steam-boilers of an electrical conductor, arranged to convey the electricity from within the boiler or steam-space to the exterior of the boiler, said conductor being insulated where it passes through the shell of the boiler, substantially as described.

2. In combination with an electrical conductor, arranged as described, I claim the use of permanent magnets, located within the boiler, substantially as set forth.

S. G. CABELL.
